UNITED STATES PATENT OFFICE.

EDWARD KRUSIUS, OF NEW YORK, N. Y., ASSIGNOR TO HAMMOND TYPEWRITER COMPANY, A CORPORATION OF NEW YORK.

TYPE-WRITER.

1,243,954.

Specification of Letters Patent. Patented Oct. 23, 1917.

Application filed July 29, 1916. Serial No. 112,015.

To all whom it may concern:

Be it known that I, EDWARD KRUSIUS, a citizen of the United States, and resident of New York, in the borough of Manhattan, 5 city and State of New York, have invented certain new and useful Improvements in Type-Writers, of which the following is a specification.

The present invention relates to improvements in typewriters, and particularly in variable spacing mechanism therefor, an object of the invention being to provide in such mechanism, means by which the spacing may take place in a positive and exact manner, 10 and variable so as to produce the proper spacing for different sized letters. A further object is to provide an improved hammer, the force of which will be automatically regulated with the changing of the 15 spacing, a small letter as will be seen, requiring a light blow, and a large letter requiring a heavier blow.

With these and other objects in view my invention is shown in the accompanying 20 drawings, and will be hereinafter more fully described with reference thereto, and finally pointed out in the claims.

In the accompanying drawings:

Figure 1 is a top plan view of a typewriter with parts removed, and showing my 25 improvements embodied therein,

Fig. 2 is a vertical sectional view,

Figs. 3 and 4 are rear views showing two 30 positions of the spacing and hammer mechanism,

Fig. 5 is a detail of the spacing means,

Fig. 6 is a detail view of the band having 35 openings through which the hammer strikes the paper,

Fig. 7 is a detail view of the slidable pawl operating member, and

Fig. 8 is a sectional view of the handle of the regulating lever.

Similar reference characters indicate corresponding parts throughout the several figures of the drawings.

Referring to the drawings, and more particularly to Figs. 1 and 2 thereof, the typewriter frame 10, which to show one embodiment thereof, is designed for the general type of typewriters known as the Hammond, in which the type are provided upon movable matrix 11 (shown in dotted lines), mounted upon the periphery of a circular 50 support 12, the type being brought into

proper position upon the initial pressure exerted upon the key 13, continued downward pressure thereon operating the hammer 14, thereby making an impression upon the paper which is inserted between the type 60 and ribbon as is well known. After printing, the carriage moves one space by means of a carriage rack 15 controlled by an escapement mechanism, to be presently more fully described, the carriage being propelled 65 by a spring (not shown), in the usual manner. A yoke member 16 is pivotally mounted between supports 17 and 18, formed upon the frame, and at its forward end is in the form of an arcuate bar 19 beneath which 70 rest the inner ends 20 of the keys 13. These ends as will be seen, are spaced from the bar 19 in rest position. In this way the type are positioned during the initial movement of the key by upward pressure on the end 75 21 of a rod which controls the movement of the respective letter on the matrix 11, the complete movement of the keys swinging the yoke upwardly. There is also mounted between the supports 17 and 18 80 above the pivot points of the yoke, a rod 22 upon which is pivotally mounted a hammer frame 23, carrying at its end the hammer 14. At one side of the frame 23 there is provided a downwardly extending arm 24 85 between the end of which and the frame there is secured a spring 25, which exerts a force upon the hammer in the direction of the type. An adjustable clamp 26 secures the spring to the frame. The yoke member 90 16 is provided at one side with a rearwardly extending arm 27 bent inwardly at 28, and provided at its end with two spaced lugs 30 and 31, between which is disposed the inwardly bent end 32 of a lever 33 pivoted 95 to the frame at 34, the said bent end extending through an opening 35 in the frame.

A hammer control lever 36 is loosely and pivotally mounted upon the escapement mechanism shaft 37 supported between suitable bearings 38 and 39 of the frame, the lever being arcuately shaped at one side of the shaft, and U-shaped as at 40 at the other side, said U-shaped portion being provided with bearing portions 41 and 42 which engage the shaft. The end of the curved portion of the lever is connected by a universal joint 43 with a projecting rod 44 on the hammer frame. An escapement wheel 45 is mounted on the outer end of the shaft, 110

and at the inner side of the bearing 38, there is provided a disk 50, both the disk and the ratchet being rotatable with or fast to the shaft. Loosely mounted upon the 5 shaft 37 there is provided a gear wheel 46 meshing with the rack 15, and a ratchet 48 movable with the gear wheel 46, and engaged by a spring pressed pawl 49 provided on the side of the disk 50. This construction 10 it will be seen permits manual movement of the rack in one direction away from its controlling spring tightening the same, and movement in the other direction by the force of the spring upon release of the escapement.

In order to permit the free manual movement in either direction, a slidable frame 47 provided at one end with a bearing 47^a, which engages the projecting reduced end 20 37^a of the shaft 37, which acts as a guide therefor, and at the other end is provided with a collar portion 47^b, which surrounds a portion of the ratchet 48 not engaged by the pawl 49.

25 A rod 105 movable with the carriage engages a bearing 106 and a recess 107 provided respectively in each side of the frame 47. This rod is controlled by thumb levers at the end of the carriage, which upon being operated, throw the rod forwardly, together with the frame 47 the projecting end 37^a of the shaft and the free space of the ratchet 48 permitting this, whereupon the beveled edge 108 of the collar 47^b raises the 35 pawl 49 from engagement with the ratchet, allowing the carriage then to be manually moved in either direction.

A lug or projection 51 is provided on the U-shaped portion 40 of the lever 36, 40 and is disposed beneath a disk 52 provided upon an upright shaft 53 journaled in the frame, and provided at its lower end with a gear wheel 54, engaged by the toothed end 55 of a bar 56, extending to the front 45 of the typewriter, and guided in its movement by slots 57 and 58 therein, engaging screws 59 secured to the frame. A series of different sized and adjustable stops 60 are provided in the disk 52 which are adapted 50 to be brought by movement of the bar 56 successively above the lug 51, the space between the end of the stop and the lug in the lower position of the lug determining the length of the spacing as hereinafter 55 more fully pointed out. The bar 56 is provided at its forward end with a pin 61, which engages the lower end of a lever 62 pivoted at 63 to a plate 64 secured to the frame. A handle 65 (Fig. 1) is provided 60 on the upper end of the lever 63, a spring controlled pin 66 being mounted therein which engages a series of holes 67 provided in the plate which correspond respectively to the stops 60, and are preferably designated by numbers. By pulling outwardly

on the handle, it will be seen the pin may be disengaged from the hole, and moved to the hole desired, this action at the same time revolving the disk 52 through the bar 56.

The lever 33 is provided with two arms 68 and 69, the arm 68 being provided at its end with a detent 70 adapted to engage the ratchet wheel 45, and the arm 69 engaging by a pin 71, a slot 72 provided in a horizontally movable member 73, mounted upon the frame by pins 74 and 75, and guided in its movement by slots 76 and 77 in said member. An enlarged portion 78 is provided on the member 73, having an arcuate slot 79 therein, circumferential with respect 80 to the ratchet wheel 45. This slot is engaged by a pin 80 provided in the end of a pawl 81 pivotally mounted upon the lever 36 and adapted to engage the ratchet wheel 45. A weighted pawl 82 pivoted to the 85 frame by means of a set screw 82^a, may be engaged with the ratchet wheel at the opposite side from the detent 81, to hold the ratchet wheel 45 when it is desired to release the detent 81 during adjustment. Tightening of the set screw normally holds the pawl 82 out of engagement.

The operation is as follows:

When the key is depressed, the initial movement as above pointed out moves the 95 proper letter into place, and upon continued movement, swings the member 16 upwardly depressing the arm 27 which moves the lever 33 downwardly, engaging the detent 70 with the ratchet wheel 45. At the same 100 time the arm 69 moves outwardly carrying with it the slidable member 73, which disengages the pawl 81 from the ratchet, whereupon the hammer by force of the spring 25 raises upon its pivot 22, and 105 strikes the ribbon and type, at the same time moving the U-shaped portion 40 of the lever 36 and the lug 51 away from the stops 60, and striking a pin 51^a which stops the hammer after it has delivered the correct 110 blow, as clearly shown in Fig. 4. When the key 13 is released, the lever 33 is moved upwardly disengaging the detent 70 from the ratchet, and moving the slidable member 73 inwardly, at the same time engaging the 115 pawl 81 with the ratchet wheel. This movement is practically instantaneous, and upon release of the ratchet by the detent 70, the same turns by reason of the free space between the lug 51 and the stop 60, this action 120 being brought about by movement of the carriage rack 15 engaging the rear wheel 46, the space between the lug 51 and the stop 60 determining the space the carriage rack is permitted to move. The hammer at 125 the same time is brought away from the type. The position of the stops 60 shown in the drawings is for the longest spacing, for use with large characters. When a smaller character is used, the corresponding stop is 130

brought into position by movement of the lever 62, thereby decreasing the space between the lug 51 and the stop. This allows a shorter movement of the ratchet wheel, and consequently of the carriage. For the shorter spacing it will be noted the lever 36 is not moved to as low a point as with the longer spacing, so that the hammer in rest position is nearer the type, and consequently there is less tension on the spring 25, so that a lighter striking force results, which is desirable with small type. In this way a sheet of paper having different types of letters will appear of uniform density, that is the smaller letters will be as light as the larger letters, by reason of the proportionate striking force exerted thereon. The arcuate slot 79 of the slidable member 73, by reason of its equal radius at all points from the shaft 37, holds the pawl 81 for any length spacing in the same relation with the periphery of the ratchet wheel, thereby resulting in the uniform and positive action thereof.

25 The universal connection between the hammer and the lever 36, and the stopping of lever 40 against pin 51^a, enables a positive and sharp striking of the hammer, and disallows any double impression, as when 30 the hammer rebounds upon the initial blow and strikes the type a second time.

A spacing bar 90 is provided at the front of the typewriter, the operating lever 91 of which extends beneath the arcuate bar 19, 35 and also beneath the end 92 of a lever 93 pivotally mounted upon a rod 94, shown in detail in Fig. 5. The end of this lever extends downwardly, and is rounded to form a cam surface 95 which engages a roller 96, 40 provided on an upstanding portion 97^a of a slidable bar 97. This bar is disposed in a slot in the frame and at its forward end extends upwardly as at 98, a slot 99 being provided therein which is engaged by a pin 100 45 of the frame, to guide its movement. The end of the bar is adapted to be moved forwardly upon depression of the cam surface 95 in such position as to engage the frame 23 and stop the hammer just before it strikes 50 the ribbon and type, thereby preventing any mark appearing upon the paper. The spacing takes place as above described. A spring 101 returns the bar to its normal position.

55 As different sized type are used, the member 110 at the upper end of the hammer 14 is turned so that the proper sized anvil surface is brought into position. At the same time the opening through which 60 the same passed must be changed. To this purpose a band 111 shown in Fig. 6 provided with a pair of different sized openings 112 and 113, is secured to the forward ends of the arms of a bow member 114, pivotally mounted at 115 and 116 upon a slidable

plate 117, secured to the frame 118 by screws 119 and 120 passing through slots 119^a and 120^a therein, which permit sliding of the plate back and forth. A spring actuated knot 121 having a pin 122 is provided on the plate for moving the same, the pin adapted to be placed in holes 123 provided in the frame 118 to properly position the spacings.

When large type are used it will be seen, the opening 112 is brought into position, 75 while with smaller type the opening 113 is used.

I have illustrated preferred and satisfactory forms of my invention, but it is obvious that changes may be made therein, within 80 the spirit and scope thereof, as defined in the appended claims.

I claim:

1. In a typewriter, a hammer, means for actuating said hammer, changeable means 85 adapted to limit the movement of said hammer, said variable position of said hammer adapted to adjust the operative force of said hammer actuating means to deliver a variable blow.

2. In a typewriter, a hammer, spring means for actuating said hammer, changeable means adapted to limit the movement of said hammer; said variable position of said hammer adapted to adjust the tension 95 of said spring means for actuating said hammer to deliver a variable blow.

3. In a typewriter, a keyboard, a carriage, means for moving said carriage, escapement means adapted to be moved by said carriage, a hammer, spring means for actuating said hammer, means connecting said hammer to said escapement means, and freely movable in one direction with respect thereto, changeable means adapted to limit the movement of said hammer and said escapement means, said variable position of said hammer adapted to adjust the tension 100 of said spring means for actuating said hammer, to deliver a variable blow.

4. In a typewriter, a keyboard, a carriage, means for moving said carriage, an escapement wheel adapted to be moved by said carriage, a hammer, spring means for actuating said hammer, a hammer control lever, a pawl on said hammer control lever, an escapement lever adapted to be engaged with and disengaged from said escapement wheel by operation of the keyboard, means adapted to engage said pawl with said escapement wheel, upon disengagement of said escapement lever, said wheel adapted to rotate upon release of said escapement lever, and changeable means adapted to limit the movement of said hammer control lever 115 with said escapement wheel, and the return movement of said hammer after striking said variable position of said hammer adapted to adjust the tension of said spring means for actuating said hammer, said pawl 120

125 mounted at 115 and 116 upon a slidable

- adapted to be disengaged from said escapement wheel upon engagement of said escapement lever therewith, to operate the hammer.
5. In a typewriter, a keyboard, a carriage, means for moving said carriage, an escapement wheel adapted to be moved by said carriage, a hammer, means for actuating said hammer, a hammer control lever, a pawl on said hammer control lever, an escapement lever adapted to be engaged with and disengaged from said escapement wheel by operation of the keyboard, means adapted to engage said pawl with said escapement wheel, adapted to rotate upon release by said escapement lever, a disk above said hammer control lever provided with changeable stops, said stops adapted to singly engage said hammer control lever, to limit the movement of said escapement wheel and said hammer after striking, and means for bringing said stops into successive operating position, said pawl adapted to be disengaged from said escapement wheel upon engagement of said escapement lever therewith, to operate the hammer.
6. In a typewriter, a keyboard, a carriage, means for moving said carriage, a hammer, means for actuating said hammer, a hammer control lever, a pawl on said hammer control lever, an escapement lever adapted to be engaged with and disengaged from said escapement wheel by operation of the keyboard, a band having openings of different sizes arranged in horizontal alinement, and means for moving said band horizontally to bring the openings into co-operating register with the hitting surfaces of said hammer.
7. In a typewriter, a keyboard provided with a spacing bar, a carriage, means for moving said carriage, an escapement wheel adapted to be moved by said carriage, a

hammer, means for actuating said hammer, a hammer control lever, a pawl on said hammer control lever, an escapement lever adapted to be engaged with and disengaged from said escapement wheel by operation of the keyboard, means adapted to engage said pawl with said escapement wheel, upon disengagement of said escapement lever, said wheel adapted to rotate upon release by said escapement lever, changeable means adapted to limit the movement of said hammer control lever with said escapement wheel, said pawl adapted to be disengaged from said escapement wheel upon engagement of said escapement lever therewith, to operate the hammer, and means operated by said space bar adapted to be projected in the path of said hammer to prevent complete striking movement thereof.

8. In a typewriter of the character described, for variable type, the combination with a hammer having changeable hitting surfaces of varied size, a band having openings of different sizes arranged in horizontal alinement, and means for moving said band horizontally to bring the openings into co-operating register with the hitting surfaces of said hammer.

9. In a variable spacing typewriter, a hammer provided with changeable hitting surfaces, of varied size, a shield provided with a plurality of varied sized openings side by side transversely for said hammer, and means for moving said shield transversely to bring said openings into alinement with said hammer.

10. In a typewriter, a traveling carriage, mechanism for effecting the letter-spacing movement of said carriage, a member mounted to turn, and a plurality of stops carried by said member and adjustable individually lengthwise of its axis, said stops being adapted to be brought selectively into the path of said mechanism to vary the extent of said spacing movement.

In testimony that I claim the foregoing as my invention, I have signed my name in presence of two subscribing witnesses.

EDWARD KRUSIUS.

Witnesses:

D. LEWIS MATTERN,
MOE WEINBERG.
